COMBINED SHELF, RACK AND TELEPHONE RECEIVER SUPPORT

Obed Fischer, Westport, S. Dak.
(Rte. 1, Box 17, Aberdeen, S. Dak. 57401)

Filed Mar. 28, 1972, Ser. No. 239,007

Term of patent 3½ years

U.S. Cl. D6—136   Int. Cl. D6—04

Fig. 1

Fig. 2

Fig. 3

Fig. 4

FIG. 1 is a perspective view of a combined shelf, rack and telephone receiver support showing my new design; FIG. 2 is a top plan view thereof;

FIG. 3 is a side elevational view thereof as seen from the left side of FIG. 2; and

FIG. 4 is a bottom plan view thereof.

I claim:

The ornamental design for a combined shelf, rack and telephone receiver support, substantially as shown.
